UNITED STATES PATENT OFFICE

DUNCAN J. STEWART, OF ROCKFORD, ILLINOIS, ASSIGNOR TO HOWARD D. COLMAN, OF ROCKFORD, ILLINOIS

SELECTOR

Application filed September 12, 1927. Serial No. 218,835.

This invention relates generally to improvements in selectors and is directed more particularly to selectors of the type commonly used in signaling apparatus.

5 One object of the invention is to provide a new and improved selector unit for a signaling apparatus which is efficient and reliable in its operation and which can be cheaply constructed by virtue of the fact that most of its 10 parts can be made from sheet metal.

Another object is to provide a novel signal responsive selector having a plurality of so-called code bars mounted for bodily movement and presentment successively to a selectively controllable pushing device and a combination member movable with said bars and normally locked against movement by the bars but adapted to be freed for movement by the setting of the bars in a particular combination.

Still another object is to provide a rotary selector unit having a plurality of notched code bars adapted in the rotation of the unit to be set by signal controlled means for effecting the selective operation of a plurality of different control devices.

Other objects and advantages of the invention will become apparent from the following detailed description taken in connection with the accompanying drawings in which:

Fig. 1 is a front elevational view of the signal receiving mechanism having a selector embodying the features of the present invention.

Fig. 2 is a schematic view of the signal control circuits for controlling the operation of the selector.

Fig. 3 is an elevational view taken from the right hand side of the mechanism shown in Fig. 1.

Fig. 4 is a sectional view taken along line 4-4 of Fig. 1.

Fig. 5 is a fragmentary detail view of the pushing device employed.

Fig. 6 is an elevational view taken from the left-hand side of the mechanism shown in Fig. 1.

50 Figs. 7 and 8 are plan and elevational views

of the contact mechanism controlled by the selector unit.

Fig. 9 is a perspective view of the selector unit and its mounting.

Figs. 10 and 11 are fragmentary perspective views showing details of the selector mechanism.

Figs. 12 and 13 are detail perspective views of a mechanism for controlling the signal receiving circuits.

Figs. 14 and 15 show developments of elements of the selector.

Fig. 16 is a plan sectional view taken along the line 16-16 of Fig. 1.

Fig. 17 is a detail view of one of the code bars.

Fig. 18 is a fragmentary schematic view of certain parts of the selector.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

The selector which constitutes the present invention is adapted for general use especially in signaling systems such as are employed in the telephone and telegraph arts. For convenience the selector is shown in the drawings in a form which is particularly adapted for use in a radiant energy signaling system which forms the subject matter of a copending application Serial No. 188,856 filed May 4, 1927 by Howard D. Colman.

This particular signaling system is intended primarily for effecting the control from a remote point of an instrumentality such as a garage door operator, and comprises generally a device on a motor vehicle adapted to transmit a predetermined codal combination of radiant energy impulses and space units and a mechanism located in the garage or other suitable place for receiving these signal units and operating when the proper combination of units is received to 100

initiate the operation of a power driven operator for opening or closing the garage door. Preferably said receiving mechanism is of the so-called start-stop type commonly employed in telegraphic signaling and is composed of a suitable signal detecting circuit and a selector mechanism whose operation for a complete signal cycle is initiated by the reception of the initial impulse of the signal combination, the remaining impulses and space units of the combination being used to control the setting of a plurality of selecting elements. The arrangement of these elements determines the character of the selection to be effected subsequently.

Generally stated, the selector proper comprises a rotatable drum adapted to be driven through one complete revolution in each signal cycle during which a plurality of so-called code bars individually movable on the drum are presented successively to a pusher which positions them in accordance with the character of the several units of the received signal. If the code bars are set in a certain combination, one or more so-called combination members carried by the drum will be permitted to move relative to the drum at the completion of the signal cycle. Movement of one combination member operates the desired instrumentality or control device which in the present instance is one of a plurality of switches.

In the present instance, the selector drum includes a horizontal shaft 20 journaled in split bearings on two standards 21 and 22 (Fig. 1) upstanding from a base frame 23. Fast upon the shaft between the standards are four flat metal disks 24, 25, 26 and 27 keyed or otherwise fixed to the shaft 20 and held in spaced relation by sleeves 28. These disks constitute supports for a plurality of code bars numbered from 29 to 42 inclusive (Fig. 14) and arranged for individual endwise movement on the drum into either of two set positions. To this end, the bars are cut from flat strips of sheet metal and extend loosely through alined apertures 43 (Figs. 9 and 10) in the disks 24, 25 and 26. Thus each bar is positioned parallel to the axis of the shaft 20 in a plane including the axis of the shaft.

To hold the bars yieldably in what will be hereinafter called "normal" position as distinguished from their "shifted" positions into which the bars may be moved by a pusher to be described later, each bar is disposed in a radially extending notch 44 in the disk 27 (Fig. 4) and is formed at its inner edge with two adjacent notches 45 (Fig. 17) adapted to engage the bottom of the notch in the disk 27. Such engagement is maintained by a light tension spring 46 acting between one end of the code bar and a wire ring 47 (Fig. 4) encircling the shaft 20. The code bars are thus adapted for bodily move-

ment transversely of their lengths and each is also adapted for endwise movement into either of two set positions where it will always be retained against accidental displacement.

Cooperating with the code bars to effect a selection according to the setting of the bars, are four so-called combination members herein comprising disks 48, 49, 50 and 51. These disks are loosely mounted on shoulders formed on the spacer sleeves 28 by which the disks are held in spaced parallel relation. Each combination disk is thus adapted for oscillatory movement about the axis of the shaft 20, the extent of which movement is determined by the length of arcuate slots 52 (Fig. 4) in the disks which receive a cross rod 53 carried by the stationary disks. For purposes, which will appear later the disks 49 and 50 are located between the stationary disks 25 and 26 while the disks 48 and 51 are positioned adjacent the disks 24 and 27 respectively.

The code bars are received in radial notches 54 formed in the peripheral edge of each combination disk and therefore act normally to lock the disks against oscillation relative to the stationary disks. However, the construction of the code bars is such that when they are set in the proper combination one or more of the movable disks will be unlocked for movement about the shaft, the desired selection being thereby made. For this purpose, each code bar is formed along its inner edge with four squared notches (Figs. 14, 15 and 17) which are slightly wider than the combination disks and deeper than the notches therein. When any code bar is positioned with one of its notches in the plane of a combination disk, that code bar will no longer hold the combination disk against oscillatory movement. Therefore, it will be seen that when all of the code bars in the series are positioned so that one notch of each registers with one of the combination disks, that disk will be free to oscillate about the shaft 20. However, if any one bar is not properly set the disk will be locked against movement.

Four different kinds of code bars are provided in the present instance, one kind being exemplified by the bars 29, 31, 33, 35, 38, 39 and 40 (see Figs. 14 and 17). These bars have four notches 55 and 56, the notches 55 being in register with the combination disks 48 and 50 when the bars are in shifted position as shown in Fig. 14 while the notches 56 are out of register with the disks 49 and 51 for the same position but in register therewith when the bars are in normal position. Similarly the bars 30, 32, 34, 36 and 37 have notches 57 which register with the disks 49 and 51 when the bars are in shifted position (Fig. 15) and notches 58 which register with the disks 48 and 50 only when the bars are in

normal position (Fig. 14). The two other kinds of bars numbered 41 and 42, are formed with double width notches 59 and 60 which always register with the disks 48 and 49 respectively and therefore never lock these disks against movement. The bar 41 has two other notches 61 and 62 which operate respectively to lock the disk 51 and unlock the disk 50 when the bar is in normal position (Fig. 14) and lock the disk 50 and unlock the disk 51 when the bar is shifted (Fig. 15). Similar notches 63 and 64 are provided in the bar 42.

As shown particularly in Fig. 4 each of the disks 48, 49, 50 and 51 is drawn forwardly, that is, in the direction of rotation of the drum by means of a spring 65 acting between the cross rod 53 and a point on the disks thereby serving to hold the trailing end 20 of the slots 52 against the rod 53. In this position of the movable disks, the notches therein register with the code bars so as to permit longitudinal movement of the latter.

The means for rotating the selector drum 25 comprises, in the preferred embodiment, a vibratory electric motor adapted to be driven at synchronous speed through one revolution of the drum during each signal cycle. Preferably the motor comprises a pair of magnetic coils 66 whose pole pieces 67 are rigidly suspended from an arm 68 projecting horizontally from a standard 69 on the frame base 23. Adjustably mounted on arms 70 depending from the arm 68 are two spring members 35 71 which support a laminated armature 72 opposite the lower ends of the pole pieces 67. This armature carries a pawl 73, the free end of which is normally held in engagement with a small ratchet wheel 74 by a spring 40 arm 74^a. A spring retaining pawl 75 engages the ratchet wheel and holds it against reverse rotation. The ratchet wheel is fast upon a shaft 76 journaled at its opposite ends in bearing arms 77 and carrying a worm 78 45 which meshes with a worm wheel 79 on the extended end of the drum shaft 20. Vibration of the armature 72 by alternately energizing and deenergizing the coils 66 operates through the connection above described to 50 rotate the drum shaft at a relatively slow and uniform speed. With this type of motor and its driving connection, the drum may be started and stopped substantially instantaneously thereby making it possible to determine 55 the extent of the rotation of the drum with the desired accuracy.

Alternate energization and deenergization of the magnet coils 66 is effected by the application thereto of alternating current power. To control the application of the power, the coils 66 are arranged in series relation and one is connected by a conductor 80 (Fig. 2) to one line 81 from the source of alternating current. The other coil is adapted 65 for connection with the other power line

82 through either of two branch conductors 83 and 84 the former having a switch 85 interposed therein which is adapted to be closed by the initial signal impulse as will be later described for the purpose of initiating the 70 operation of the driving motor. The conductor 84 has interposed therein a switch 86 which is adapted to be closed by the initial movement of the drum and to be closed for the remainder of the signal cycle thereby 75 maintaining a continuous connection between the coils and the power lines.

To close the switch 86 upon the initial movement of the selector drum and open it after one revolution thereof, a disk 87 having 80 a notch 88 therein is made fast upon the shaft 20 adjacent the worm wheel 79. Herein the peripheral portion of the disk bears against a spring follower 89 carrying one contact of the switch 86 and presses this contact against 85 another contact on a spring arm 90 (Figs. 12 and 13) except when the shaft 20 is at rest after the completion of a signal cycle. In this position (Fig. 13), the end of the follower 89 drops into the notch 88 and allows 90 the switch 86 to open. As shown in Fig. 16, the spring arms 89 and 90 are mounted on an insulating block 91 secured to the base 23.

In the rotation of the drum during each signal cycle the code bars are presented successively to a pusher which operates under the control of the received signal units to move the bars endwise into shifted position or to allow them to remain in normal position according to the character of the different 95 signal units corresponding to the respective code bars. Preferably the power for pushing the bars endwise is derived from the rotation of the selector drum, the application of such power being controlled by a signal responsive 100 device to be later described.

The pusher comprises a light sheet metal member 92 which may be termed a plow and which has two spaced ears formed at one of its ends and pivoted on a vertical pin 93. As 110 shown in Figs. 5 and 9, the pin is supported by a bracket 94 secured to the frame standard 22 and carries a light coil spring 95 acting to swing the plow toward the disk 24. At its free end the plow is formed with an 115 inclined portion 96 (Figs. 14 to 16) which is normally disposed in the path of the ends of the code bars.

Because of the tendency of the springs 46 to hold the code bars in normal or shifted 120 positions, movement of the bars by engagement with the plow 92 is resisted and this resistance is sufficient to overcome the action of the spring 95. Therefore unless the plow is restrained against pivotal movement when a bar in normal position is presented, the spring 95 will yield and permit the plow to move out of the path of the bar. In case the plow is restrained against pivoting when a code bar is presented, the inclined portion 130

96 acts as a cam on the end of the bar and causes the bar to be pushed from normal to shifted position.

During each revolution of the selector drum 5 each code bar which is in shifted position as a result of having been pushed in the previous signal cycle is moved back to normal position just prior to its presentation to the pusher. As is best shown in Fig. 16, the 10 means for thus resetting the code bars comprises a stationary cam 97 whose face is located at the end of the drum opposite the pusher and in position to engage the ends of the code bars. This cam is formed on a plate 15 98 secured upon the frame standard 21.

In order that the code bars will be set during each signal cycle in a combination corresponding to the arrangement of units in the received signal, means is provided for 20 controlling the movements of the pusher so that if a signal unit of one character is received the plow will be restrained against pivotal movement and the code bar thereafter presented will be moved from normal to shifted 25 position. On the other hand, if the signal unit is of a different character, the plow will be free to move out of engaging relation with the code bar. The means herein employed for accomplishing these results includes a control finger 99 (Fig. 5) which is adapted for movement vertically into and 30 out of the space between a lateral lug 100 on the plow and a fixed abutment provided by a plate 101. When in blocking relation, as 35 shown in Fig. 5, the finger prevents pivotal movement of the plow as the latter is engaged by one of the code bars, the result being that the bar then engaging the plow is shifted endwise by the force resulting from the continued 40 forward movement of the drum.

In the present instance, the finger 99 is in the form of a lug depending from the side edge of a plate 102 carried by an arm 103 which projects rearwardly from the armature 104 of a sensitive electromagnet having coils 105. As shown in Figs. 5 and 16, the plate 101 is secured upon the right hand frame standard 22 with one side edge projecting therefrom just above the level of the lug 100 45 and terminating at such a distance from the end of the lug as to allow for movement of the finger 99 into and out of blocking position. The armature 104 is supported by pivots 106 on arms 107 which project downwardly 50 from an overarm 108 secured to the frame standard 69. This arm also supports the magnet coils 105 through the medium of their pole pieces 109. A light spring 110 acting between the arm 103 on the armature and a 55 leaf spring 111 (Fig. 3) tends to swing the armature away from the pole pieces 109 thereby tending to raise the control finger 99 out of locking position. Preferably the spring 110 is relatively short in length so that its 60 tension will change rapidly to conform to

changes in the attractive force of the electromagnets 105 on the armature which force decreases rapidly as the air gap between the armature and the pole pieces is widened. Thus the spring tension is greatest when the air gap is narrow and smallest when the air gap is widest and the attractive force is small. The magnet therefore is extremely sensitive.

Normally, that is, when no signal impulses are being received the magnet coils 105 remain energized by means to be later described, the armature 104 being thereby drawn upwardly against the action of the spring 110 with the result that the arm 103 is pressed down against the plate 101 with the control finger in blocking position between the lug 100 on the plow and the abutment formed by the edge of the plate 101. Accordingly, when the magnet coils 105 are deenergized, the finger 99 is raised by the action of the spring 110 so that the lug 100 is free to move under the plate 101 when a code bar on the rotating drum engages and swings the plow. In order that the control finger cannot be withdrawn after a code bar has once engaged the plow and is thereby being positioned according to the position of the control finger at the time of such engagement, the end of the lug 99 is formed with an inclined surface 112 (Fig. 5) which is adapted to cooperate with the inclined end portion 113 of the control finger. Thus, the force due to the reaction of a code bar on the plow while the bar is being pushed thereby serves to press the surfaces 112 and 113 together with the result that the control finger will be held in blocking position until the bar has passed the plow even though the magnet coils do become deenergized while the bar is still in operative position with respect to the plow.

The means for detecting the transmitted signals and controlling the magnet 105 according to the character of the individual units, is shown diagrammatically in Fig. 2, 110 and comprises a grounded circuit 114 having an antenna 115 therein. This circuit is associated by means of an inductive coupling 116 with the input or controlling circuit 117 of a detector tube 118 which circuit includes the 115 grid 119 and filament 120 of the tube. For the purpose of tuning the control circuit, a variable condenser 121 is connected across the secondary coil of the coupling 116. The filament of the tube is heated continuously, 120 the source of alternating current being used for this purpose through the medium of a step-down transformer 122.

The plate or control circuit of the tube includes a conductor 123 connecting the plate 124 to one terminal of the magnet coil 105, the other terminal of the coil being connected by a conductor 125 to the conductor 80 and thence to power line 81. A conductor 126 between the power line 82 and the filament 120

120 completes the plate circuit. Alternating voltage is thus impressed across the plate and filament but the current in the plate circuit is unidirectional owing to the rectifying action of the tube.

5 The receiving circuit just described operates by the well known grid-condenser method to maintain the magnet coils 105 energized when no radiant energy impulses 10 are being received by the antenna, the armature 104 of the magnet being thereby drawn upwardly to press the control finger downwardly into blocking position. When a train 15 of radiant energy waves constituting an impulse of the signal is detected, negative charges are produced on the grid 119 which causes the current in the plate circuit to decrease sufficiently to deenergize the magnet 105 thereby causing the control finger to be 20 withdrawn from blocking position.

The leakage resistance between the filament and the grid of the vacuum tube is kept as high as practicable in order that relatively weak signals can be detected. Therefore, 25 after the magnet has been deenergized by the reception of a radiant energy impulse, the negative charges caused thereby are retained on the grid so that before the succeeding unit of the signal, which may be a space unit in- 30 stead of an impulse, can be effective to control the setting of the next code bar, to be presented to the pusher, it is necessary to recondition the tube and thereby energize the control magnet 105. This is accomplished 35 by discharging the grid of the tube just after each code bar has engaged the plow and been controlled thereby. To this end, a wheel 127 is made fast upon the shaft 20 and formed with a plurality of teeth 128 which engage 40 a follower 129 and periodically close a switch 130 during each signal cycle. One contact of the switch comprises a spring arm 130^a (Fig. 6) and is carried by the follower 129 which is connected to the grounded power 45 line 82 through a conductor 131 (Fig. 2). The other switch contact is on a binding post 132 connected to the conductor 117.

There is one tooth 128 on the grid discharge wheel 127 corresponding to each code bar on 50 the selector drum each tooth being positioned with respect to the selector drum so that it will, in the rotation of the shaft 20, reach the end of the follower 129 just after a code bar has engaged the plow 92 and is being 55 controlled in accordance with the position of the control finger 99 at the time of such engagement. This relation is shown schematically in Fig. 18. Closure of the grid discharge switch is only momentary owing to 60 the shortness of the teeth 128. After the termination of each grid discharge, the tube will be in condition to respond to the next signal unit whether it is an impulse or a space unit. In this way, the signal cycle is divided up 65 into a plurality of control periods during

which an impulse may be received to properly control the code bars corresponding to the respective periods. Each period occupies the time interval between the termination of the grid discharge and the engagement between the plow and the code bar next to be presented to the plow after opening of the switch 130. If an impulse is received at any time during one of these periods whether near the beginning or the end of the period, it will withdraw the control finger and allow the code bar to pass the plow without being pushed.

70 Breaking of the running circuit of the driving motor by opening of the switch 86 at the end of the signal cycle causes a radiant energy field to be created by electromagnetic induction around the receiving circuit, the tendency of which would be to deenergize the magnets 105 and start the motor for another cycle by closing the starting switch 85. To obviate this difficulty, means is provided for rendering the receiving circuit inoperative at the time the switch 86 is opened, this being accomplished in the present instance 80 by continuing the last grid discharge of each signal cycle until after the switch 86 has been opened. This means (Figs. 12 and 13) includes a disk 133 loosely mounted on the shaft 20 adjacent the wheel 127 and having a lost motion connection 133^a (Fig. 6) with the wheel 127. A spring 134 (Fig. 6) tends to oscillate the disk 133 in the direction of rotation of the shaft and thereby normally holds the disk in the position shown in Fig. 13. The disk 133 has a lug formed with an arcuate surface 135 located substantially the same distance from the axis of the shaft 20 as an elongated tooth 136 on the wheel 127, the trailing edge of which tooth terminates 90 the last grid discharge. The follower 129 is wide enough to contact the surface 135 and also the tooth 136.

100 Projecting laterally from the lug on the disk 133 is an arm 137 which engages a lug 138 on the follower 89 near the end of the signal cycle, the follower being at this time in contact with the raised peripheral portion of the disk 87. Thus, the lug 138 constitutes a stop which holds the disk 133 back so that the surface 135 prevents opening of the grid discharge switch 130 even though the trailing end of the tooth 136 may have been carried beyond the end of the follower 129. However, when the end of the follower 89 drops into the notch 88 to open the motor circuit, the lug 138 thereon moves out of the path of the arm 137 and frees the disk 133 for movement by its spring 134. In such movement, the trailing end of the surface 135 is carried 110 beyond the end of the follower 129 and the follower is allowed to move into the depression on the wheel 127 and opens the grid discharge switch, the receiving circuit being left 115 in proper condition for the next signal cycle. 120

The first impulse of each signal is utilized to start the motor of the selector drum. This is accomplished by mounting on the armature 104 the movable contact 139 of the switch 85 (Fig. 1) for closing the temporary starting circuit of the motor. The stationary contact of this switch is disposed below the armature and is formed on the end of a screw 140 threading through a plate 141 (Fig. 6) which projects forwardly from an insulating block on the selector frame. Since the armature is drawn upwardly by energization of the coils 105 when no code signals are being received, the switch 85 is normally held open. However, when any radiant energy impulse is detected which is of sufficient strength to cause the magnet 105 to be deenergized, the switch 85 will be closed by the action of the spring 110. This establishes the temporary energizing circuit for the motor and holds that circuit closed until the grid of the vacuum tube is discharged by rotation of the selector drum sufficiently to carry the first tooth of the wheel 127 against the follower 129. In the initial movement of the drum, the switch 86 is closed and the main energizing circuit for the drum motor takes control for the remainder of the signal cycle.

The selection according to the character of the received signal combination is completed in the present instance by the use of yieldable stops which are positioned to engage the combination disks after all of the code bars have been presented to the plow and just before the selector drum has completed its revolution. Herein the stops are in the form of rollers 142 (Figs. 6, 7, 8, 10 and 11) mounted on the free ends of spring arms numbered 143 to 148 inclusive and secured to an insulating block 149 which is mounted on the front of the frame standards 21 and 22. Each follower projects over the selector drum and normally bears against a limit stop 150 (Fig. 6). In this position, the rollers on the followers 143, 145, 146 and 148 are disposed respectively in the paths of raised cam lobes 151 on the combination disks 48, 49, 50 and 51. Near the end of the signal cycle the leading ends 152 of the cam lobes engage the rollers 142 on the followers and tend to hold the combination disks back against further rotation with the drum. If at the time the combination disks are thus restrained, the code bars are set so that one notch in each bar registers with one of the combination disks thereby forming an arcuate groove, that disk will be held stationary momentarily, continued movement of the selector drum independently of the disk thus held being permitted by the groove formed by the aligned notches. The limit of such relative movement between the disk and the drum is determined by the length of its slot 52. Further movement of the selected combination disk relative to the drum is thus prevented

and in the continued rotation of the drum, the follower is pressed outwardly with its roller riding along the cam lobe. As the trailing end of the cam lobe passes beyond the roller, the follower is allowed to move back to normal position. The combination disk being then no longer restrained in its movement, is moved forwardly and therefore restored to normal position by its spring 65. This conditioning of the combination disk for the next cycle takes place just before the movement of the drum is arrested by opening of the motor circuit. In the event that the code bars are not set in any one of the four proper combinations when the cam lobes strike the rollers 142, relative movement between the combination disks and the stationary disks on the drum cannot take place. Under these conditions all of the followers are forced outwardly as soon as they are struck by the cam lobes.

According to the present arrangement of notches in the code bars as shown in Figs. 14 and 15, the combination disk 48 will be freed for movement whenever the code bars 29, 31, 33, 35, 38, 39 and 40 are shifted out of normal position, the bars 41 and 42 are either shifted or not shifted and the other bars remain in normal position. If the bar 42 is also shifted and the bar 41 is not shifted by the same signal, the disk 50 will also be permitted to move. In a similar way the notches are aligned to permit movement of the disk 49 when the bars 30, 32, 34, 36 and 37 are shifted while the other bars remain in normal position. The disk 51 will move simultaneously with the disk 49 when the bar 41 is also shifted and the bar 42 is not shifted.

Relative movements between the combination disks and the stationary disks are utilized respectively to operate four control devices herein illustrated as comprising four switches 153, 154, 155 and 156 (Figs. 7 and 8). The switches 153 and 154 are formed by arms 157 on the followers 143 and 145 positioned to cooperate with one of two contacts on the spring follower 144 also secured to the insulating block 149. The switches 155 and 156 are formed by contacts on the arm 147 cooperating with contacts on arms 158 carried by the followers 146 and 148. Normally the arms 143 to 148 are pressed down against the stop 150 their contacts being disposed as shown in Fig. 8 with all of the switches open.

The rollers 142 carried by the arms 144 and 147 are positioned respectively in the paths of cam lobes 159 formed on the stationary disks 25 and 26. The angular position of the leading ends of these lobes is such that the rollers 142 are engaged thereby at substantially the same time the lobes 151 engage their rollers. Thus if the combination disks are locked against movement at the end of the cycle, all of the followers will be pressed

outwardly simultaneously thereby maintaining all of the switches open. On the other hand, if one combination disk is freed by the proper setting of the code bars to move relative to the adjacent stationary disk, its follower will be actuated shortly after the follower actuated by the stationary disk, the result being to momentarily close the switch controlled by the two followers whose movements thus take place successively.

With the code and combination bars constructed as above described, it will be observed that switches 153 and 154 will be closed by the different settings of the code bars which free the combination disks 48 and 49 respectively. The switch 155 will be closed at the same time as the switch 153 provided the code bars 41 and 42 are properly set by the last two units of the signal so as to free the disk 50. Similarly, if a space unit causes the bar 41 to be pushed and an impulse allows the bar 42 to remain in normal position following the signal units which properly set the other bars to close the switch 154, the switch 156 will also be closed. Closure of the switches 153 and 154 may be utilized to initiate the operation of power operators of two different doors of a garage as is disclosed in a copending application by Howard D. Colman, Serial No. 188,856 filed May 4, 1927. Switches 155 and 156 may be used to control the lighting circuit in the garage in accordance with the operation of the respective doors, a means for accomplishing this result being disclosed in my copending application Serial No. 177,555 filed March 23, 1927.

The operation of the selector during a signal cycle may be briefly summarized as follows: For example, by a signal composed of fifteen units of which units 1, 3, 5, 7, 9, 10 and 14 are represented by radiant energy impulses while the others are space units. Upon the reception of the first signal impulse, the magnet 105 is deenergized which closes the switch 85 to establish a temporary starting circuit for the motor magnet 66, thereby initiating the rotation of the selector drum which establishes the main circuit for the motor. In such rotation, each code bar not already in normal position is shifted into normal position by the cam 97. During the reception of the remaining signal units, the code bars 29, 31, 33, 35, 38, 39, 40 and 42 will be pushed into shifted position under the control of the space units of the signal while the bars 30, 32, 34, 36, 37 and 41 remain in normal position. Thus the bars will be arranged as shown in Fig. 14, the combination disks 48 and 50 being thereby freed for oscillation upon the drum. Near the end of the revolution when the lobes on the stationary and combination disks strike the rollers of their respective followers, the followers 144, 145, 147 and 148 will be pressed outward-

ly owing to the fact that the disks 25, 49, 26 and 51 are at this time rigid with the selector drum. Disks 48 and 50, however, being free to oscillate, will be held back momentarily so that outward movement of their followers will be delayed slightly. Since the followers 144 and 145 and the followers 147 and 148 move simultaneously switches 154, and 156 remain open. The followers 144 and 143 and followers 147 and 146, however, move successively, the prior actuations of the followers 144 and 147 serving to close the switches 153 and 155. After the lobes have passed the follower rollers, the disks 48 and 50 are returned to normal position by their springs 65. The main motor switch is then opened as the follower 89 drops into the notch 88, the signal cycle being thereby terminated. This movement of the follower 89 releases the disk 133 for movement to finally terminate the last grid discharge.

I claim as my invention:

1. A selector for a signalling system comprising, in combination, a plurality of code bars mounted in parallel relation for bodily movement transversely of their lengths and for individual endwise movement into either of two set positions, driving means operable to effect such bodily movement, signal responsive means controlling said endwise movement, a notch in each of said code bars, a combination member mounted for movement perpendicular to said bars and positioned in register with the notches in certain of said bars when the bars are in normal set position and in register with the notches in said other bars when the latter bars are in said other set position, said member being thereby locked against movement by said last mentioned group of bars when they are in normal set position and by the remaining bars when such bars are in said other set position, means operable to move said member relative to said bars when all of the notches are in register with said member, and a control means operable in such relative movement between the member and the bars.

2. A selector for a signalling system comprising, in combination, a rotatable drum, a plurality of code bars supported in parallel relation around said drum and adapted for individual movement parallel to the drum axis, signal responsive means operating in the rotation of said drum to selectively position said bars, a plurality of notches in each of said bars, one notch in each bar cooperating with the corresponding notches in the other bars to provide an arcuate groove when the bars are set in a predetermined combination, a plurality of combination disks each mounted on said drum for oscillation perpendicular to the axis of said drum in the groove formed by one of the sets of notches, all of said disks being locked against movement when the code bars are set in any other than the predeter-

- mined combinations, and a plurality of control devices each responsive to the oscillation of one of said disks.
3. A selector for a signalling system comprising, in combination, a plurality of parallel code bars supported for bodily movement transversely of their lengths and for individual movement into either of two set positions, a plurality of notches in each of said bars, one notch in each bar cooperating to provide an elongated groove when the bars are set in a predetermined combination, a plurality of combination elements mounted for movement along with said bars, one for each set of notches adapted to be freed for movement relative to said bars by the alignment of one set of notches, and signal controlled means controlling the individual setting of said bars.
4. A selector for a signalling system comprising, in combination, a supporting means, a plurality of code bars mounted in said supporting means having notches therein and arranged in parallel relation for bodily movement and also for individual endwise movement into either of two set positions, said code bars being held by said supporting means against movement in a direction transversely of their lengths, a pusher device normally disposed in the path of the bars successively presented thereto and adapted by engagement with each bar to shift it out of normal set position or to yield and allow the bar to pass unpushed, a control element movable into and out of blocking relation with said pusher, and a combination member cooperating with the notches in said bars so as to be controlled in its movements by the setting of said code bars by said pusher device.
5. A selector for a signalling system, comprising, in combination, a supporting means, a plurality of bars mounted in said supporting means and arranged in parallel relation for bodily movement transversely of their lengths and adapted for individual endwise movement only relative to the supporting means, a combination element member normally engaging certain of said bars and held thereby against movement, notches in said bars cooperating when said bars are set in a predetermined combination to provide a groove for permitting movement of said element, and signal controlled means deriving energy from the bodily movement of said bars and operable to set said bars in said predetermined combination.
6. A selector for a signalling system comprising, in combination, a plurality of notched code bars adapted for individual movement into either of two set positions, signal responsive means controlling the setting of said bars, two combination members associated with each of said bars and normally locked against movement relative to said bars, and a pair of notches in each of said bars positioned to permit movement of only one of said members when said bars are set in one combination and to permit movement of both of said members when said bars are set in a different combination.
7. A selector for a signalling system comprising, in combination, a plurality of selecting elements, signal controlled means for selectively positioning said elements in different combinations, a pair of members controlled in their movements by the setting of said elements, one of said members being responsive to a predetermined setting of said elements and both of the members being responsive to a predetermined different setting of the elements.
8. A selector for a signalling system comprising, in combination, a plurality of selecting elements, signal controlled means for selectively positioning said elements in different combinations, and a control member normally held against movement by a plurality of said elements and arranged to be freed for movement in response to the setting of said elements in either of two different combinations.
9. A selector for signalling systems having, in combination, a rotatably mounted shaft, driving means for rotating said shaft through a predetermined cycle, a pair of relatively thin disks fixed upon said shaft and spaced apart lengthwise of the shaft, a plurality of code bars supported near their opposite ends in said disks for individual movement only relative to the disks, a signal responsive device controlling the setting of said bars in the rotation of the shaft through said cycle, and a combination element also in the form of a disk mounted on said shaft but capable of limited rotation relative thereto, said combination disk having transverse notches in its peripheral edge, and said code bars having portions normally entered in said notches and acting only when the code bars are set in a predetermined combination to permit independent movement of the combination disk with respect to said bars, means acting to effect such independent movement of the combination disk at the end of said cycle, and a control means operable as an incident to such independent movement.
10. A selector for signalling systems comprising, in combination, a plurality of rigid code bars, a combination element, a rotary carrier on which said code bars and combination element are mounted with the code bars arranged for individual endwise movement transversely of the combination element, said code bars on the one hand and the combination element on the other being arranged for limited relative rotation, and said code bars having at points between their ends portions normally coacting with said combination element to permit such relative rotation only.

when the code bars are set in a predetermined combination, means operable to rotate said carrier through a predetermined operating cycle, a non-rotatable signal responsive device positioned for the successive presentation thereto of said code bars and operable to effect the endwise movement of the latter selectively, means operable near the end of the cycle to cause said member to move independently of the code bars when the latter are set in said predetermined combination, and a control means acting as an incident to such independent movement.

In testimony whereof, I have hereunto affixed my signature.

DUNCAN J. STEWART.
